CLAIM

The ornamental design for a furniture panel, as shown and described.

DESCRIPTION

FIG. 1 is a front elevational view of the furniture panel of the instant invention.

FIG. 2 is a bottom view of the furniture panel shown in FIG. 1.

FIG. 3 is a top view of the furniture panel shown in FIG. 1.

FIG. 4 is an end view of the furniture panel shown in FIG. 1. The opposite end view is the mirror image of FIG. 4.

The undisclosed rear surface of the panel is essentially flat and unadorned.

FIG. 3

FIG. 1

FIG. 4

FIG. 2
